E. E. KLEINSCHMIDT

METHOD OF AND APPARATUS FOR OPERATING PRINTING TELEGRAPHS

Filed May 1, 1919

UNITED STATES PATENT OFFICE.

EDWARD E. KLEINSCHMIDT, OF BROOKLYN, NEW YORK, ASSIGNOR TO THE KLEIN-SCHMIDT ELECTRIC COMPANY, A CORPORATION OF NEW YORK.

METHOD OF AND APPARATUS FOR OPERATING PRINTING TELEGRAPHS.

Application filed May 1, 1919. Serial No. 293,949.

To all whom it may concern:

Be it known that I, EDWARD E. KLEIN-SCHMIDT, a citizen of the United States, residing in New York, borough of Brooklyn, in the county of Kings and State of New York, have invented certain new and useful Improvements in Methods of and Apparatus for Operating Printing Telegraphs, of which the following is a specification.

10 My invention more particularly relates to the operation of a telegraph system in which each station is equipped with a transmitting device, such as a tape-controlled device and with a receiving device, and in which information, such as groups of electric impulses corresponding in code to a letter, is alternately transmitted between the two stations in opposite directions. Hitherto, in a duplex telegraph system of this general character, it has been usual to use an artificial line in order that the relay at the transmitting station may not be affected by the electric impulses sent out from the transmitting station. In such a system, however, the 25 characteristics of the artificial line must be kept the same as those of the main line joining the two stations, and as the latter is affected by external influences, such as the weather, its characteristics vary, with the 30 consequence that the artificial line must frequently be adjusted in order that its capacity, self-induction, etc. may be kept the same as that of the main line, and such adjustment necessitates the presence of a skilled electrician.

35 One of the objects of my invention is the provision of a telegraph system in which information, represented in general by groups of electric impulses, is alternately transmitted in opposite directions between the two stations and automatic means, such as a rotating distributor, is provided at each station for alternately closing the line circuit through the transmitting and the receiving 40 means.

45 Another object of my invention is the provision of means for properly correlating the movements of the distributors or other automatic controlling means.

50 Other objects of my invention will appear from the specification, and will be more particularly pointed out in the claims.

My invention will best be understood by reference to the accompanying drawing,

which illustrates diagrammatically a printing telegraph system embodying my invention.

Referring, now, to the drawing, in which I have shown one embodiment of my invention, A and B are two stations similarly equipped to send and receive messages, and connected by a main-line wire 38. The two stations are provided with transmitting devices which are diagrammatically indicated and are represented by the reference letters C and D, respectively. These transmitting devices may be constructed in any well known manner, though I preferably make the same in accordance with the invention covered by my application Serial No. 293,950, which was filed in the Patent Office of even date with my present application, and which relates to a transmitter operated by a perforated tape. The receiving devices or printers of the two stations are diagrammatically represented by a series of magnets E and F, respectively, and may be constructed in accordance with any well-known receiving device, though preferably constructed in accordance with the invention covered by my Patent No. 1,448,750, issued March 20, 1923.

As the apparatus and wiring of two stations A and B are the same, I will describe the same with reference to station A only, the apparatus and wiring at station B being indicated by similar reference numerals, but with the letter "b" appended. In the drawing, 1 is a motor which drives a gear 2 preferably through a worm and worm gear, as shown, the latter being secured on a shaft 3, it being understood that a friction drive is provided between the worm gear and shaft in order that the shaft may be held stationary while the motor is continuously rotating. A stop arm 4 is secured to the shaft 3 and is arranged to engage one arm of an elbow lever, which is normally held in position to engage the arm 4 and which stops the rotation of the arm 4 and the shaft during each rotation. A brush arm 5 is secured to the outer end of the shaft 3, and is provided with two sets of brushes 6 and 7 insulated from each other, which bear against a stationary commutator 8. I have, for convenience, referred in the claims to a rotating distributor, and in the embodiment of my invention here shown, it will be un-

derstood that this element corresponds to the rotating brushes. The commutator is divided into two sections, 81 and 82, respectively, the insulation dividing the two sections being indicated in general at 83. The transmitting segments 9 and 10 are connected to stationary contacts 11 and 12 of the transmitter C, while the transmitting segments 13, 14, 15, 16 and 17 are respectively connected to movable contacts 18, 19, 20, 21 and 22 of the transmitter C. One pole of the line battery 23 is connected through a resistance 24 to the contact bar 11, while the other pole of the battery is connected through the resistance 25 to the contact bar 12, the middle of the battery being grounded as shown. Segment 26, which is disposed on the receiving section of the distributor 8 diametrically opposite the segment 10, is connected to a starting magnet 27, the other terminal of which is grounded as shown. Segment 28 of the transmitter is connected to the contact point of the polarized relay 29 with which the armature 30 engages when it is moved to the left. The armature of this relay is connected through a resistance 31 and a battery 32 to the ground. Receiving or selecting segments 33, 34, 35, 36 and 37 are connected to the respective receiving magnets of the printer E. The relay 29 is connected to the line 38 and to the segment 39 on the receiving side of the commutator 8. A segment 40 on the receiving side of the commutator is connected by a conductor 41 to the ground. Segment 42 on the transmitting side of the commutator, is connected by a conductor 43 to the line 38 at a point beyond the relay 29. Segment 44 of the commutator is connected by a conductor 45 to a stationary contact 46 of a circuit breaker, the movable contact 47 of which is mounted on a spring arm 48, the spring arm being connected through the conductor 49 to the start or sixth-impulse magnet 50, and through the battery 51 to the ground, so that the circuit of the magnet 50 is closed at each rotation of the distributor provided the contacts 46, 47 are closed. In a printing telegraph system of the general character illustrated, a printing magnet (not shown herein) is used for printing the characters. The start or sixth-impulse magnet is a relay controlling the circuit of the printing magnet. The contact 47 is moved away from the contact 46 by one section 52 of a compound arm 53, the other section of which is designated by the numeral 54. The two sections 52 and 54 are pivoted together at 55 so that the section 52 is free to move in a horizontal plane with respect to the section 54, while the section 54, and accordingly the whole arm 53, is pivoted for movement in a vertical plane on a pivot 56 on a bracket, as shown. The section 52 is drawn against a stop 57 by a spring 58 and a spring 59

tends to force the free end of the section 52 into engagement with the shaft 3. The end of the section 52 is provided with a lug extending at right angles to the section, as shown, which lug engages a worm 61 secured on the shaft 3. Normally, therefore, when the spring 59 holds the free end of the arm 53 in engagement with the shaft, the worm 61 moves the lug 60 towards the gear 2, and an insulating member 62, which is formed thereon, engages the spring finger 47 and carries the movable contact out of engagement with the stationary contact 46. The lug 60 is carried out of engagement with the worm by means of a magnet 64 which attracts an armature 63 on the free end of the section 54 when the magnet is energized. One terminal of the magnet 64 is grounded, while the opposite terminal is connected by a conductor 65 to one of the terminals of each of the magnets of the printer E, so that the magnet 64 is energized while the magnets of the printer are energized.

In my application Serial No. 293,950, above referred to, an operating magnet is shown which is energized before the transmitting brushes of the distributor pass over the corresponding transmitting segments and which acts to feed the perforated tape forward in the interval between the transmission of electric impulses over the line. This magnet is here indicated by the reference numeral 66, and its circuit includes a movable contact 67 which co-operates with a stationary contact 68, the movable contact being mounted on a spring finger 69. The spring finger is operated by a cam 70 secured on the shaft 3 so that the contacts are closed once during each revolution of the shaft. A battery 71 is included in this circuit. A shunt circuit 72 around the armature 30 of the relay 29 is controlled by a contact finger 73 and is connected between the wire leading to the segment 28 and to the conductor which extends from the armature 30 to the ground.

In the drawings, the instruments at each of the stations are shown at rest with the exception of the motors, which are continuously rotating. Now, when the operator at either station desires to send a message, he will depress the contact finger 73, thereby closing a circuit from the ground through the battery 32, resistance 31, contact 73, conductor 72, conductor 28, brushes 7, segment 26 and magnet 27 to the ground, thereby energizing the starting magnet 27 and causing the same to attract an armature 75 on one arm of the bell crank lever 74 and release the opposite arm from engagement with the arm 4 secured on the shaft. The shaft then begins to rotate, and the brushes carried by the brush holder 5, which is secured thereto, are carried over the commutator. As the brushes pass over

the segments of the transmitting side 82, no effect is produced on the system, as the distributor at the other end of the line has not yet begun to rotate. When the brushes 5 7, however, reach the segments 9 and 42, a circuit will be closed from the ground through the battery 23, resistance 24, contact bar 11, segment 9, brushes 7, segment 42, conductor 43, line conductor 38, polarized relay 29^b, segment 38^b, conductor 41^b to the ground. The relay 29^b is thereby energized, but with a current in a direction to move the armature 30^b to the right and away from the contact at the left. The 10 purpose of sending this impulse, which may be termed a clearing impulse, is to place the relay tongue in proper position to receive the following starting impulse which immediately follows when the brushes 15 engage the contacts 42 and 10. This circuit is the same as the one just traced, with the exception that the left side of the battery 23 is connected through the resistance 25 and contact bar 12 to the segment 20 10, and thence to the brushes 7 and the segment 42, the remainder of the circuit being the same as that just traced. The impulse now sent over the line will again energize the polarized relay 29^b, but 25 30 since the impulse is in the opposite direction from that sent over the line when the brushes were in engagement with the contacts 9 and 42, the armature 30^b is now moved in the opposite direction and against its contact, thereby closing a local circuit at station B from the battery 32^b through the resistance 31^b, armature 30^b, segment 28^b, brushes 7^b, segment 26^b, starting magnet 27^b to the ground. Magnet 27^b is 35 40 thereby energized and releases the arm 4^b, and the commutator 8^b begins to rotate. The beginning of the segment 10 is diametrically opposite the segment 26, so that the distributor 8^b begins to rotate with its 45 50 brushes 180° behind those of the distributor 8, the brushes 7 of the commutator 8 then passing in succession over the transmitting segments 13, 14, 15, 16, 17 and the segment 12, thereby transmitting message impulses 55 60 over the line in accordance with the code determined by the combination set up in the transmitter C, as more fully explained in my application Serial No. 293,950, above referred to. While the 65 70 brushes of the commutator 8 are passing over the segments 13, 14, 15, 16 and 17, the brushes 7^b of the commutator 8^b will pass over the segments 33^b, 34^b, 35^b, 36^b and 37^b, respectively, thereby energizing 75 80 the proper magnets of the printer F through local circuits comprising the battery 32^b, resistance 31^b, armature 30^b, segment 28^b, brushes 7^b and the respective magnets of the printer F, and through the conductor 65^b and magnet 64^b to the 85 90 ground. Now, when the brushes 7 come into engagement with the segment 26, the arm 4 will be in a position to engage the elbow lever 74 and momentarily stop the rotation of the commutator 8. As the 95 100 brushes 7^b continue to rotate they will come into engagement with the segments 9^b and 42^b on the transmitting side of the commutator 8^b and send a clearing impulse from the battery 23^b at the station B, which 105 110 station now becomes the transmitting station, to the station A, which is now the receiving station, in precisely the same manner as the clearing impulse previously described as being sent from station A to station B. Then, as the brushes come into contact with the segments 10^b and 42^b, a starting impulse of opposite polarity will be sent from station B, which causes the magnet 27 at station A to be energized, 115 120 thus causing the brushes 7 at station A to start rotating and to pass over the receiving segments 33, 34, 35, 36, 37 at station A, while the brushes 7^b at station B are passing over the transmitting segments 13^b, 14^b, 15^b, 16^b and 17^b of the commutator 8^b. It will thus be apparent that groups of impulses designating letters will be alternately transmitted between the stations A and B in opposite directions, and 125 130 since the distributing brushes at each station begin to rotate over the receiving side of the commutator in response to an impulse passing through the transmitting side of the other commutator, the rotation of the two distributors is so correlated that the brushes of the one distributor are passing over the receiving segments while the brushes of the other distributor are passing over the transmitting segments, and as this 135 140 relation is automatically maintained, it will be apparent that no provision is necessary for compensating for the lag in the line. 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

From the description already given, it will be apparent that the magnet 64 is energized and the contacts 46 and 47 are accordingly closed during the time that the magnets of the printer F are energized, or, in other words, while a message is being received, and that when no message is being received the magnet 64 is de-energized and the contacts 46 and 47 opened, thereby rendering it impossible to actuate the start or sixth-impulse magnet 50.

It is undesirable to operate a start magnet when no messages are being received.

What I claim and desire to secure by Letters Patent of the United States is:

1. A printing telegraph system comprising a rotary distributor divided into signal receiving and transmitting sections, a stop position for said distributor immediately preceding said signal receiving section, means for transmitting a start impulse immediately preceding said signal transmit-

ting section, a start-stop magnet for said distributor, a receiving relay adapted to complete local energizing circuits through said start magnet and said receiving distributor section, and a shunt circuit around said receiving relay arranged to permit the completion of a local energizing circuit through said start relay.

2. The combination as set forth in claim 10 1, and a shunt circuit from said transmitting section, around said receiving relay.

3. The combination as set forth in claim 2 at each of two stations so arranged that the distributors operate to alternately transmit to and receive from the opposite station.

4. In a printing telegraph system, a rotary distributor, a drive shaft for said distributor, a plurality of receiver selectors controlled by said distributor, a receiver operating means controlled by said distributor and also controlled by means carried by said distributor shaft.

5. The combination as set forth in claim

4 in which the receiver operating means 25 comprises an operating magnet.

6. The combination as set forth in claim 5 in which said operating magnet is energized from a circuit interrupted by said last mentioned means.

7. The combination as set forth in claim 6 in which said last mentioned means comprises a contact arm, and a screw carried by said distributor shaft adapted to actuate said arm.

8. The combination as set forth in claim 7 in which said contact arm is carried by an electromagnet armature, and an electromagnet controlled by said distributor adapted to actuate said armature.

In testimony whereof, I have hereunto signed my name in the presence of two subscribing witnesses.

EDWARD E. KLEINSCHMIDT.
